UNITED STATES PATENT OFFICE.

JAMES D. LA TIER, OF WATERLOO, IOWA.

VERTICAL-SWING DOOR FOR SILOS.

1,046,611.

Specification of Letters Patent. Patented Dec. 10, 1912.

Application filed September 5, 1911. Serial No. 647,641.

To all whom it may concern:

Be it known that I, JAMES D. LA TIER, a citizen of the United States of America, and a resident of Waterloo, Blackhawk county, 5 Iowa, have invented certain new and useful Improvements in Vertical-Swing Doors for Silos, of which the following is a specification.

My invention relates to improvements in 10 vertical swing doors for silos, and the object of my improvement is to provide for a silo which has a continuous vertical door opening, closures adapted for superposed arrangement in closing said opening, and 15 which are hinged so as to swing vertically upward or downward as desired for convenience of access to the interior of the silo, and to avoid undue disturbance of the ensilage therein. This object I have accomplished by the means which are hereinafter 20 described and claimed, and which are illustrated in the accompanying drawings, in which:

Figure 1 is a front exterior elevation of 25 the part of a silo which contains the continuous vertical door opening, showing my improved vertically swinging doors in position therein. Fig. 2 is a side elevation of 30 one of the swing doors and its hinged connections to one of the side frames of the door opening of the silo. Fig. 3 is a rear elevation of the brace-connection between the side frames of said door opening. Fig. 4 is a 35 plan view of the brace-connection shown in Fig. 3.

Similar numerals of reference designate corresponding parts throughout the several views.

It is in this invention, my purpose to 40 part from the usual method of securing door closures to silos, which are generally hinged at the side to swing horizontally, or made removable. My improved method of hanging the doors is intended to be used in silos 45 which have a vertical continuous door opening extending nearly if not entirely throughout their height.

I have shown in Fig. 1 merely the horizontal sills 2 and 3, and the vertical side 50 frames or beams 1-18 of the vertical continuous door-opening of a silo. The side-beams 1-18 are connected and braced by means of the brace-connections 11, which are made preferably of metal. Each brace 11 55 has longitudinal strengthening ribs 16 and 21 on opposite sides, and has at each end on

its outer face a lug 15, in which are secured by means of nuts 19 the ends of the rods 4, the latter being passed around the silo under tension to hold the structure together and 60 assist in supporting the stress of the outwardly-pressing weight of ensilage within the silo. On each end of the brace 11 adjacent to the lugs 15 are upwardly and downwardly extending ears 12 and 13 respectively, provided with bolt-holes adapted to receive bolts 14 to secure them to the side-beams 1. On the rear face of each brace 11 and spaced apart from its ends, are lugs 17 65 projecting rearwardly at right angles to the brace, and which are adapted to engage the inner faces of the beams 1. Each lug 17 is provided with an orifice or socket opposite the socket in the other lug, and adapted to serve as bearings for the outturned ends of 70 the arms of the door-hinge 7.

The door 5 is rectangular and adapted to fit between the beams 1-18. The ends 20 of the doors are rabbeted so as to be counterparts of each other to fit together closely 80 when in position closing the door-opening, and is shown in Fig. 2 particularly, where the dotted lines represent the positions of the door while at its uppermost and lowermost positions in being engaged or disengaged, and the same view showing in full lines the position of the door and its hinge when extended into the silo interior to the fullest extent. The door 5 is hinged so as 85 to swing vertically by the following means. 90

The numeral 7 designates a horizontal shaft movable to rock in bearings 9 on the raised braces 6 on the outside of the door. The ends of said shaft outside or beyond 95 said bearings are bent away therefrom at right-angles, and the ends of the bent away arms thus made are again bent to the side again or offset at right-angles and seated to rock in the bearing-openings in the lugs 17 of said brace-connections 11. The said 100 arms 8 of the shaft 7 thus are suitably mounted to swing to and from the beams 1, carrying the medially suspended door 5 with them, either vertically upward or downward as may be desired. It will be 105 observed that the interference of a door so suspended is much less with the ensilage in the silo, than is the case when a horizontally-swinging door is used, for the movement of the door being vertical, half at least 110 of its swing is free from interference with the ensilage which would lie usually below

the medial horizontal line of the door. Since the door is disengaged as indicated in the dotted lines of Fig. 2, when the ensilage is being withdrawn, there is but little interference and but little necessary displacement of the ensilage behind the door, for the door escapes upwardly obliquely, sliding away from the ensilage behind, and not pushing into it bodily. In the same way, it is easy to place and secure the door in its proper location superposed on the door below, when filling the silo, by withdrawing it from its upper to bring it into its lowered position. When in place, the door is secured to the beams 1 by means of turn-latches 10, or any other convenient detachable fastening-means.

Having described my invention, what I claim as new, and desire to secure by Letters Patent, is:

A silo having a continuous vertical opening, spaced apart cross-pieces connecting the sides of said opening, a series of doors for

closing said opening, such doors being rabbed at their tops and bottoms to fit one against another, a hinging member for each door pivotally connected to one of the cross-pieces and to the door, said hinging-member comprising horizontally spaced apart bearings located in the medial horizontal line of the door adjacent to its vertical edges, a rock-shaft seated in said bearings and having an arm at each end bent at similar angles and having their ends oppositely offset outwardly and seated in bearing brackets on the cross-piece, said door being adapted to be swung bodily up or down to fit parts of said vertical opening on either side of the cross-piece to which its hinging-member is pivoted.

Signed at Waterloo, Iowa, this 19th day of Aug. 1911.

JAMES D. LA TIER.
